GARMENT RENEWING MACHINE

Colin Gordon MacBride, London, England

Application October 19, 1946, Serial No. 704,456
In Great Britain September 16, 1944

17 Claims. (Cl. 26--28)

1

This invention relates to garment-renewing machines of the type in which the fabric to be treated is placed upon a support and is pressed upon by a rotary rubbing face to which may be supplied a fluid which comes between said face and the fabric.

In machines of the type stated as hitherto used, the rubbing face is presented by a single rotary device. The rotary device consists of a holder in which is inserted an abrasive disc suitable for giving appropriate pile-raising or other renewal treatment to a garment. This device must be worked over the surface of the fabric, including seams, with the result that the rate of progress is slow.

The rotary device, which presents a rubbing face, is embodied in a so-called pressure head. In use of the machine a worker holds the pressure head by a control handle and presses the rotary device upon the work. The magnitude of the pressure applied by the rotary device to the fabric is a vitally important factor in the performance of the work, so much so that the sense of feel in a worker must be developed by thorough training before she can use one of these machines successfully.

An object of the present invention is to make provision in a machine of the type stated whereby a reliable indication of the pressure being exerted on the work is continuously presented to the worker so that she is enabled to maintain the pressure at some predetermined magnitude without relying upon her own sense of feel.

Another object of the invention is to provide in a machine of the type stated a plurality of rotary fabric-renewing devices which are applicable under pressure to the fabric and which are spaced around the axis of a pressure head whereby in they are incorporated, the rotary devices being respectively geared with a central drive.

Another object is to provide in such a machine a plurality of normally co-planar rotary fabric-renewing devices applicable simultaneously under pressure to the fabric and in which the rotary devices are individually movable against spring devices in relation to one another to allow resistance in relation to one another to allow for formations such for instance as seams on, or varying textures in, the fabric. The movements of which the devices are individually capable may comprise vertical and tilting movements.

The pressure head may have a handle so supported that by manipulation of the handle the head and the assembly of rotary devices therein incorporated can be turned about the axis of the

2

pressure head to suit the lie of the work on the garment support.

Another object of the invention is to provide in such a machine an assembly of rotary devices mounted in the pressure head so as to be displaceable as an assembly in the head against a yielding spring resistance when working pressure is applied to the pressure head.

Yet another object is to provide in such a machine locking means, preferably automatic, to hold the one or more rotary devices down to their work.

In a preferred form, the machine has one or more rotary fabric-renewing devices arranged on a holder and adapted to be applied to the work against spring pressure, such application involving relative movement between said holder and devices and a pressure gauge on said holder operatively connected to the one or more devices and adapted by the relative movement to give an indication of the applied pressure. The machine also includes an overhead support, an extensible connection between said overhead support and the holder on which the one or more rotary devices are arranged and a locking device serving to lock said holder against return movement relatively to said support when said connection is extended by the application of working pressure to a magnitude indicated by the gauge.

30 A garment-renewing machine embodying the invention will now be described by way of example with reference to the accompanying drawings in which:

Fig. 1 is an elevation of the machine in out-of-use position, portions of parts being broken away and shown in section for clearness. Fig. 2 is a section on the line 2-2 of Fig. 1, being drawn to a larger scale. Fig. 3 is a plan of parts constituting the top of the machine. Fig. 4 is an elevation partly in section, of parts shown in Fig. 1, but lowered into their working position, this view also being drawn to a larger scale than Fig. 1. Fig. 5 is a mid-section of parts of the machine as shown in Figs. 1 and 4, being drawn to a still larger scale, and Fig. 6 is a similar view of other parts. Fig. 7 is a fragmentary sectional elevation of the component herein referred to as the pressure head, the section being approximately on the line 1-1 of Fig. 9. Fig. 8 is a sectional plan of the pressure head, the section being on the line 8-8 of Fig. 1 and the view being drawn to a larger scale. Fig. 9 is a fragmentary section approximately on the line 9-9 of Fig. 7, certain of the parts being broken away to show parts below them. Fig. 10 is an

inverted plan of one of the rotary fabric-renewing devices fitted with an annular brush.

The means whereby the working components of the machine are supported comprise a base 1, a vertical post 2 at one side of the base and a horizontal jib 3, extending overhead across the base from the top of the post, a motor-carrying structure 4 from which a pressure head 5 depends being carried by and immediately below the jib and a buckboard 6 constituting the garment support being mounted on the post. The jib and the buckboard are connected respectively at 7 and 8 to the post, and either one of the connections may be a swivel whilst the other is rigid with the post. Thus, provision is made for relative lateral movement between the pressure head and the work, which is denoted by 9, Fig. 4. To ensure steadiness in use of the machine the base has a three-point support, namely three runners or casters 10, one of which is located near the post at the rear of the base and the other two of which are near the front corners thereof. The base has a cabinet 11 which can be equipped as a garment-drying receptacle by fitting it with appropriate air heating means.

The pressure head 5 includes an assembly of three rotary fabric-renewing devices 12, although any desired plurality may be used. The devices (see Fig. 7) are connected to rigid vertical shafts 13 journalled in a locating plate 14 which consists chiefly of three radial arms. The holder of the devices 12 and plate 14 is a casing 15. The plate 14 is vertically displaceable in the casing 15, being guided by arcuate flanges 16 at the ends of its arms sliding against faces 17 in the casing. The flanges 16 have feathers 18 that are slideable in slots 18A formed in the faced portions of the casing 15 to hold the plate 14 and the rotary devices 12 against turning movement relatively to the casing 15 around the vertical axis of the casing. That is to say, the devices 12 are confined to rotation about their own axes. Each device-carrying shaft 13 is polygonal in cross-section and has a gearwheel 19 connected to it, and the three gearwheels 19 are arranged around a central gearwheel 20 with which they mesh in the manner of planet-wheels with a sun-wheel. The central gearwheel is keyed to a rigid vertical rotary shaft 21 forming a part of a telescopic driving shaft dependent from overhead. The device-carrying shafts 13 are capable of limited vertical movement relatively to the plate 14 through the gearwheels 19, which are journalled in ball-bearings 22, 23 on the plate 14 and are held against vertical movement relative thereto by an abutment nut 24 on the elongated boss 25 of each of these gearwheels. Small strong springs 26 are interposed between the rotary devices 12 and the associated abutment nuts 24 to oppose upward movement of the rotary devices and their shafts 13 relatively to the plate 14. A set screw 27 on each shaft 13 limits its downward movement, the arrangement being such that each rotary device 12, when pressed upon the work 9, can rise in relation to the pressure head in general and the plate 14 in particular independently of the other rotary devices 12.

Each of the rotary devices is connected to the shaft 13 that rotates it by a universal joint, namely a part-ball 28 engaging in a socket 29 which is a part of the associated rotary device 12, the ball and socket having arcuate feather-and-groove connections 30 with one another (see Fig. 7). The arrangement is such that each rotary device 12 is not only capable of being forced up-

wards independently of the others but can adopt a position askew to the axis of its shaft 13, for example if necessitated by the contour of the top surface of the work 9 when the rotary device is pressed thereon. The springs 26 serve not only to oppose yieldingly any relative upward movement of the rotary device but also any tendency to adopt an askew position. In Fig. 4, rotary devices 12 are shown pressed upon the work but not raised relatively to the plate 14. However, in the event that a rotary device should encounter a raised portion of the work 9, say a seam, that device will be forced to rise relatively to the others and will tilt itself, by virtue of its universal joint 28-30, in so far as may be necessitated by the lie of the work.

The previously mentioned telescopic driving shaft also includes a length 31 the lower end of which is formed as a socket 32 which is slidably connected with the other shaft part 21. The part 21 and socket 32 are polygonal in cross section. The foot of the shaft part 21 is supported by a foot-step ball-bearing 33 in the boss 34 of the plate 14 and the other shaft part 31 is journalled in a ball-bearing 35 in the casing 15.

A compression spring 36 is interposed between a collar 31A on the shaft 31 and the central gearwheel 20, said spring functioning to urge the entire assembly of movable parts constituting the active components of the pressure head towards their lowermost position, in which they are shown in Figs. 1 and 7. This lowermost position is determined by the feathers 18 engaging detachable stops 18B which close the otherwise open bottom of the slots 18A provided for the feathers in the casing 15. Thus, when the rotary devices 12 are brought into engagement with the work 9, sufficient downward pressure on the casing 15 forces them, together with the gearwheels 19 and 20 driving them and the plate 14 supporting them, as an assembly upward in relation to the casing 15, the extent of movement being proportional to the magnitude of the downward pressure. In this relative movement, the shaft part 21 telescopes in the socket 32, the spring 36 being compressed.

The casing 15 is suspended from the motor-carrying structure 4 by a telescopic tubular shaft assembly, comprising an outer tube 37 secured by a fixture 38 to the base of the structure 4, an inner tube 39 secured to the handle 40 of the casing 15, an intermediate guide sleeve 41 interposed between upper and lower portions of the outer tube 37 and a locking case 42 secured to the foot of the outer tube and serving inter alia as a guide for the inner tube. Relative turning between the tubes 37 and 39 is prevented by a feather 43 and groove 44 in the tubes 39 and 37 respectively, said feather and groove forming a connection which permits the tubes to telescope.

The pressure head 5 is supported by tension springs 45, which if desired may be enclosed in telescopic cases (not shown). The springs 45 are attached to lugs on the fixture 38 and to lugs on a collar 46 secured to the inner tube 39. In Figs. 1 and 4, the spring 45 therein shown is broken away to show parts behind it.

The telescopic tubular shaft assembly 37-41 and the central driving shaft 21, 31, 32 constitute a rigid connection between the motor-supporting structure 4 and the pressure head 5, permitting only vertical movement of the pressure head in relation to the structure 4. Nevertheless, the entire suspensory structure comprising the motor-supporting structure 4, the pressure head 5 and the inter-connecting shafting is

freely turnable angularly about its vertical axis, is freely movable lengthwise of the buckboard 6 and is freely movable relatively to the buckboard crosswise thereof. The free angular movement is got by virtue of a swivel mounting at 47 between the top of the structure 4 and a trolley boss 48 on the jib 3 (see Figs. 2 and 3). The free lengthwise movement is got by virtue of the trolley boss 48 having two upper pairs of wheels 49 and two under pairs of wheels 50 all journaled on arms 51 and riding upon rails 52 shown as ledges formed in two side-by-side members constituting the jib 3. The free relative crosswise movement is got by virtue of the previously mentioned pivotal mounting of the jib or the buckboard on the post 2. All of the movements of the pressure head are got by application of the requisite forces to the handle 40 on the part of the operator. In regard to the angular movement, such is got by appropriate manipulation of the handle 40, for instance in order to align the rotary devices 12 with formations such as seams or ridges on the surface of the fabric constituting the work 9. That is to say, it might be desirable to work one device (or two devices) along a raised surface of the fabric beyond a longitudinal, transverse or inclined seam whilst working the other two devices (or other one device) over the main surface alongside the seam, the differences in level being automatically allowed for by appropriate yielding of the springs 26 individual to the devices.

The arrangement is such that the pressure head with or without the garment-supporting buckboard can be moved about by the operator as the work progresses, in order to bring any portion of the work under the action of the pressure head.

The drive to the rotary devices is imparted to their central driving shaft 31 by an electric motor 53 through intermeshing gearwheels 54, 55. The motor is supported by a bracket 56 on the carrying structure 4, being arranged with its axis vertical. The gearwheel 55 is journaled in ball-bearings 57 (see Figs. 2, 4 and 5) in a bracket 58 secured to the structure 4. The shaft 31 has a sliding connection with the gearwheel 55, the uppermost portion of the shaft and the bore of the gearwheel being polygonal in cross-section. Thus, in the falling and rising of the shaft 31 with the pressure head 5 to and from the buckboard 6, the gearwheel 55 remains located in its bearings.

Each rotary device 12 comprises mainly a disc 59 made of rubber or other abrasive material (see Fig. 7), the disc being clamped in place by a ring holder 60. A brush 61 may be used in combination with each disc with the objects of cleaning and otherwise preparing the texture of the fabric 9 for treatment by the disc, removing from the fabric liquid supplied thereto through the disc, and raising and improving the nap of the fabric after such treatment. In the example, the holder 60 of each disc 59 is adapted to receive an annular collar 62 (see also Fig. 10) which is faced with the brush material 61, for instance bristles or hair, and which is secured to the holder by means of say a bayonet joint 63, or otherwise as may be convenient. Instead, the arrangement might be such that each disc is removable from its holder and is replaceable by a circular brush of substantially the same size as the disc. A machine having such brushes for use in place of the abrasive discs can be used for dry surface cleaning of garments.

The machine shown is equipped with an overhead reservoir 64 for the chemical liquid to be supplied to the pressure head for application through the rotary devices 12 and rubber discs therein to the fabric preliminary to the usual treatment with the liquid. The reservoir 64 is mounted on the motor-carrying structure 4, which is made as a closed housing for the motor 53 and associated gearing and for the reservoir. The liquid is led through piping 65 to the handle 40, which is provided in known manner with an internal self-closing valve (not shown) adapted to be opened by depression of a finger lever 66 on the handle. Piping 67 from the handle leads to branches 68 (Figs. 7 and 8) having three small control valves 69 from each of which extends a supply spout 70 directed upon the inner wall 71 of an annular chamber 72 on the associated rotary device 12. The chamber 72 of each device opens through ports 73 to the active face of the disc 59.

The motor-supporting structure 4 also encloses a switch connected in the motor circuit and adapted automatically to start and stop the motor 53 when the pressure head 5 is lowered for and returned from work. In the example, the automatic switch is of the fluid type, comprising a tiltable tube 74 made of a suitable insulating thermo-setting plastic (such as that marketed under the trade-mark "Bakelite"). The tube 74 is carried by a lever 75 (Fig. 2) fulcrumed on a bracket 76 secured to a wall of the structure 4. The lever is acted upon by a spring 77 that holds, or strives to hold, the lever 75 against a stop 78, the tube 74 then being in a position in which the fluid—namely, mercury or an electrically-conducting oil—makes contact between the switch terminals, which are connected in the motor circuit. The tube is arranged to co-operate with a striker 79 on top of the shaft 31. The arrangement is such that when the pressure head 5 is permitted by the worker to rise to the position according to Figs. 1 and 2, the striker 79 upturns the switch 74, 75 and the fluid breaks contact, thus stopping the motor. Conversely, when the pressure head 5 is lowered towards the work, the striker 79 falls from the lever 75, and the spring pulls the switch into the motor-starting position, so that by the time the rotary devices 12 reach the work 9 they are rotating at full speed.

In the machine shown, provision is made for holding the rotary devices down to their work against the upward pull of the springs 45 upon the inner tube 39, so that the work will continue under the pressure of the spring 36, such pressure being proportional to the extent to which the spring 36 is compressed by the operator in forcing the pressure head 5 upon the work (Fig. 4). The means provided consist of an automatic one-way clutch 80 housed in the previously mentioned locking case 42, which is secured to the outer tube 37 and embraces as a guide to the inner tube 39. The clutch 80 (Fig. 6) is of the known ring type sometimes referred to as a "friction pawl," the ring being formed so as to encircle loosely the inner tube 39 and its inner periphery being edged so that the ring bites the inner tube 39 when the ring adopts the fully inclined position in which it is shown. One side 70 of the clutch ring rests at 81 upon the bottom of the locking case 42; and the ring cooperates with the stop 82 depending from the cover of the case 42. The clutch ring 80 automatically adopts the locking position in which it is shown 75 because of its tendency to fulcrum about the

stop 82 and bite hard upon the inner tube 39 under the urge thereof to rise under the pull of the springs 45, the arrangement being such that the ring effectively prevents upward movement of the inner tube so long as the ring adopts its fully inclined position.

The clutch ring is capable of locking the inner tube 39 only against upward movement; that is to say if downward pressure is applied by the operator to the pressure head 5, when raised, the clutch ring cannot hinder downward movement of the pressure head, the inner tube 39 sliding downwards freely through the ring.

A finger piece 83 is arranged diametrically opposite to the stop 82, projecting freely through the bottom of the case 42 and engaging the ring 80. In the event that the pressure head 5 is lowered and the inner tube 39 is locked by the ring 80 against rising, the operator can pull down the ring 80 by means of the finger piece 83 into a non-locking position, in consequence of which the springs 45 pull the pressure head upwards into the out-of-use position.

A spring 84 may be provided to expedite and render surer the automatic action of the ring when adopting and maintaining its locking position. It is convenient to arrange the stem of the finger piece 83 through the spring 84, if a spring is provided.

In the machine shown, a pressure gauge 85 is provided on the casing 15 of the pressure head in order to indicate to the worker the magnitude of the pressure being applied to the fabric 9 by the rotary fabric-renewing devices 12 collectively. As shown in Fig. 7, the plate 14, which rises and falls as part of the assembly of working parts within the casing 15, is connected at 86 to a rod 87 the top of which is formed at 88 as a rack, which forms a component of the pressure-gauge mechanism. This mechanism also includes a pointer 89 (Fig. 8) co-operating with a graduated scale 90 marked with any appropriate values or units, such for instance as lbs. per square inch, indicative of the total pressure applied by the rotary devices. The pointer is connected in known manner through appropriate gearing (not shown) within the gauge 85 to the rack 88.

The buckboard 6 consists of a single ironing board or the like. The board may form one of a number of such boards, respectively made for different classes of work. These boards are made so that any selected one of them may be rigidly attached to the connection 8 provided for them on the post 2 of the machine. Any appropriate means of attachment may be provided. For example, as indicated by Fig. 1, the board 6 may have secured to its underside a channel 91 which is adapted to slide firmly upon a T-section arm 92 extending horizontally from the connection 8. A device 93, such as a set-screw or a spring catch, may be provided on the channel 91 for locking thereof to the arm 92 in the proper positional relationship of the board 6 to the connection 8.

The garment renewing machine is operated in the following manner:

When the machine is not in use, the pressure head 5 adopts its raised position, in which it is shown in Fig. 1. The motor 53 is then stopped and the valve controlled by the finger lever 66 is closed, so that the rotary devices 12 are at rest and the supply of liquid from the reservoir 64 is shut off.

In order to use the machine, a buckboard 6

suitable to the work is secured to the connection 8. Thereafter, a fabric 9 constituting the work is appropriately placed upon the buckboard.

The operator grasps the handle 40 and presses down the pressure head 5, against the pull of the springs 45, towards the work, depressing the lever 66 in the usual manner as the work is reached in order to start the flow of liquid by way of the valves 69, which are open to a previously regulated extent. As the operator lowers the pressure head, the inner tube 39 slides freely through the clutch ring 80; moreover the striker 79 is retracted from below the lever 75, with the result that the switch 74 is tilted to close the motor circuit and thus start the motor 53. Accordingly, by the time that the rotary devices 12 reach the work (Fig. 4), the devices are rotating at full speed and liquid is being supplied to the work through the ports 73. The operator continues the downward pressure in order that the rotary devices will exercise the desired working pressure upon the fabric. Accordingly the spring 38 is forced to yield by the assembly of working components within the casing 15. Meantime, the operator watches the pointer 89 of the gauge 85. When the pointer reaches a mark suitable for the working pressure to be exercised upon the work in hand, the operator ceases to press downwards upon the handle 40, with the result that the automatic clutch ring 80 bites into the inner tube 39 and locks the entire suspensory apparatus against withdrawal from the work. The upper reaction against the suspensory apparatus by the work is taken by the lower trolley wheels against the rails of the jib 3. The operator now moves the pressure head 5 over the work, turning the pressure head if desired about its vertical axis by swivelling at 48, or moving the pressure head laterally by movement of the trolley along the jib 3, or effecting relative crosswise motion between the pressure head and the buckboard 6 about the axis of the post 2.

In the foregoing description of the operation of the machine, the three rotary devices 12 are considered as an assembly. In the event that one or more of these devices encounter formations on the fabric different from the general plane of the work, such device or devices will automatically adjust itself or themselves by virtue of the springs 26 and universal joints 28, as hereinbefore explained.

In the event that one or more of the rotary devices are being inadequately or excessively supplied with liquid, appropriate adjustment is made to the associated valves 69.

When the work in hand is completed, the operator pulls down the finger piece 83, thus unlocking the clutch ring 80 with the result that the springs 45 lift the pressure head 5 into the out-of-use position. As usual the operator releases the finger lever 66, so that the supply of liquid is shut off. As the out-of-use position is approached, the striker 79 returns the switch 74 to its raised position, in which the motor circuit is opened and the motor stopped.

The machine hereinbefore described with reference to the drawings is an example embodying the invention and is subject to modifications. For example, in a machine not having a locking device, such as the automatic one-way clutch 80, and not having a pressure gauge to indicate the working pressure, the drive from the overhead motor to the pressure head need not consist of rigid members such as the driving shaft 21, 31

and the tubular supporting means 31, 39 but may consist of a flexible cable drive such as is already known in machines of the type to which this invention relates.

I claim:

1. A garment-renewing machine comprising a support upon which is placed a fabric to be treated, a pressure head arranged above said support, a plurality of rotary fabric-renewing devices incorporated in said pressure head, said devices being applicable under pressure to the fabric on the support, means for rotating said devices, said rotating means including a central drive and gearing between said drive and said devices, and means holding said head against turning by said rotating means so as to confine said devices to rotation about their own axes.

2. A garment-renewing machine comprising a support upon which is placed a fabric to be treated, a pressure head arranged above said support, a plurality of rotary fabric-renewing devices incorporated in said pressure head, said devices being applicable under pressure to the fabric on the support, a driving shaft centrally arranged in relation to said pressure head, a motor which drives said shaft, a central gearwheel on said shaft, gearwheels which are connected to the individual rotary devices and mesh with said central gearwheel, and means holding said pressure head against rotation by said motor and gearwheels so as to confine said devices to rotation about their own axes.

3. A garment-renewing machine comprising a support upon which is placed a fabric to be treated, a pressure head arranged above said support, a plurality of rotary fabric-renewing devices incorporated in said pressure head, said devices being applicable under pressure to the fabric on the support, driving means for rotating said devices and including a rigid driving shaft, a rigid suspensory tubular support for the pressure head, said driving shaft and tubular support being both telescopic to allow for lowering and raising of the pressure head to and from the fabric support, and means holding said pressure head against turning by said driving means so as to confine said devices to rotation about their own axes.

4. A garment-renewing machine comprising a support on which can be placed a fabric to be treated, a plurality of normally co-planar rotary fabric-renewing devices applicable simultaneously under pressure to the fabric on the support, means for driving said devices to rotate, said means including gear-shafts individual to the devices, pivot connections between said gear-shafts and devices by virtue of which connections the devices are tilttable in relation to one another, and spring means serving to resist tilting movement of the individual devices.

5. A garment-renewing machine comprising a support on which can be placed a fabric to be treated, a plurality of normally co-planar rotary fabric-renewing devices applicable simultaneously under pressure to the fabric on the support, said devices being movable in relation to one another, spring means serving to resist movement of the individual devices from their normal co-planar relationship, a holder in which said devices are journaled, driving means extending through said holder and operatively connected to the respective devices to rotate them, a swivel support from which said holder and driving means are suspended and hand means on the holder for turning it and said devices to suit the lie of the fabric.

6. A garment-renewing machine comprising a buckboard for fabric to be treated, a plurality of rotary fabric-renewing devices applicable simultaneously under pressure to the fabric on said buckboard, a suspensory support for said rotary devices, spring means serving to maintain said support raised when out of use but yielding so that said support can be lowered when the rotary devices are to be pressed down upon the fabric, and a spring associated with said support against the resistance of which spring the rotary devices are pressed down.

7. A garment-renewing machine comprising a buckboard for fabric to be treated, an overhead support, a structure with a motor and pivotally connected to said support, a pressure head incorporating a plurality of rotary fabric-renewing devices movable both as individuals and as an assembly in relation to the pressure head regarded as a whole, spring means resisting movement of said devices as an assembly, spring means resisting movement of said devices as individuals, a telescopic support between said structure and the pressure head by virtue of which telescopic support the pressure head can be lowered and raised to and from the fabric on the buckboard, and a telescopic drive between said motor and said rotary devices by virtue of which telescopic drive said devices can rise and fall not only with the pressure head but in relation thereto.

8. A garment-renewing machine comprising a buckboard for fabric to be treated, a plurality of rotary fabric-renewing devices applicable simultaneously under pressure to the fabric on said buckboard, a suspensory support for said rotary devices, said support being lowered when the rotary devices are to be pressed down upon the fabric, a spring associated with said support against the resistance of which spring the rotary devices are pressed down, and a one-way clutch device applied to said suspensory support for locking the devices down to their work upon the fabric under the pressure of said spring.

9. A garment-renewing machine comprising a buckboard for fabric to be treated, an overhead support, a structure with a motor and pivotally connected to said support, a pressure head incorporating a plurality of rotary fabric-renewing devices movable against spring resistance both as individuals and as an assembly in relation to the pressure head regarded as a whole, a telescopic support between said structure and the pressure head by virtue of which telescopic support the pressure head can be lowered and raised to and from the fabric on the buckboard, a telescopic drive between said motor and said rotary devices by virtue of which telescopic drive said devices rise and fall not only with the pressure head but in relation thereto, and one-way locking means applied to said telescopic support for holding the rotary devices pressed against the fabric on said buckboard under action of said spring resistance.

10. A garment-renewing machine comprising a buckboard for fabric to be treated, an overhead support, a structure with an electric motor and pivotally connected to said support, a pressure head incorporating a plurality of rotary fabric-renewing devices movable both as individuals and as an assembly in relation to the pressure head regarded as a whole, spring means resisting movement of said devices as an assembly, spring means resisting movement of said devices as individuals, a telescopic support between said structure and the pressure head by virtue of which telescopic support the pressure head can be low-

ered and raised to and from the fabric on the support, a drive between said motor and said rotary devices, a switch for controlling the starting and stopping of said motor, and a striker for operating said switch, said striker being arranged in the pressure head so as to rise and fall with the pressure head so that the motor is in operation only when the pressure head is lowered.

11. A garment-renewing machine having a pressure gauge, at least one rotary garment-renewing device which is axially movable, a manually depressible member connected with said gauge for moving said device axially to impose pressure upon a garment to be renewed, spring means interposed between said depressible member and said device to yieldingly oppose depression of said member relatively to said device, and an operative connection between said gauge and said device so as to cause the gauge to give an indication of the pressure of the device on the garment.

12. A garment-renewing machine which has one or more rotary fabric-renewing devices applicable under pressure to a fabric, a suspensory support for said one or more rotary devices, said support being lowered when the one or more rotary devices are to be pressed down to work upon the fabric, a spring associated with said support against the resistance of which spring the one or more rotary devices are pressed down, and a pressure gauge operatively connected to said one or more devices to give an indication of the pressure exerted against the spring resistance by said one or more devices when pressed down.

13. A garment-renewing machine comprising an overhead support, a structure supporting a motor and pivotally connected to said support, a pressure head incorporating one or more rotary fabric-renewing devices movable against spring resistance in relation to the pressure head regarded as a whole, a telescopic support between said structure and the pressure head by virtue of which telescopic support the pressure head can be lowered and raised to and from its work, a telescopic drive between said motor and said one or more rotary devices by virtue of which telescopic drive said one or more devices can rise and fall not only with the pressure head but in relation thereto, and a pressure gauge operatively connected to said one or more devices to give an indication of the pressure exerted against the spring resistance by said one or more devices when pressed down in relation to the pressure head.

14. A garment-renewing machine having one or more rotary fabric-renewing devices arranged on a holder and adapted to be applied to a garment to be renewed, spring means interposed between said holder and said one or more devices, said devices being movable relatively to said holder against the pressure of said spring means in order to work upon the garment, and a pressure gauge on said holder operatively connected to the one or more devices and adapted by the relative movement to give an indication of the applied pressure.

15. A garment-renewing machine having one or more rotary garment-renewing devices, a bearing member in which said one or more devices are journalled, a holder in which said member and one or more devices are movably arranged, spring means resisting movement of said bearing member and one or more devices in relation to said holder, a pressure gauge on said holder, an operative connection between said gauge and member such that the gauge gives an indication of the movement of the bearing member and one or more devices in relation to the holder against the resistance of said spring means.

16. A garment-renewing machine which has one or more rotary fabric-renewing devices applicable under pressure to a fabric, a bearing member in which said one or more devices are journalled, a suspensory holder for said bearing member and one or more rotary devices, said holder being lowered when the one or more rotary devices are to be pressed down upon to work the fabric, a spring associated with said holder against the resistance of which spring the bearing member is movable in relation to said holder when the one or more rotary devices are pressed down, and a pressure gauge operatively connected between said holder and bearing member to give an indication of the pressure exerted against the spring resistance by said one or more devices when pressed down.

17. A garment-renewing machine having an overhead support, one or more rotary fabric-renewing devices arranged on a holder and adapted to be applied to the work against spring pressure, such application involving relative movement between said holder and devices, an extensible connection between said overhead support and said holder, a pressure gauge on said holder operatively connected to the one or more devices and adapted by the relatively movement to give an indication of the applied pressure and a locking device serving to lock said holder against return movement relatively to said support when said connection is extended by the application of working pressure to a magnitude indicated by the gauge.
